(57) **CLAIM**

I claim the ornamental design for a trolley case, as shown and described.

DESCRIPTION

FIG. 1 is a front perspective view of a trolley case according to the present invention;

FIG. 2 is a right side elevational view thereof;

FIG. 3 is a left side elevational view thereof;

FIG. 4 is a rear elevational view thereof;

FIG. 5 is a front elevational view thereof;

FIG. 6 is top plan view thereof; and,

FIG. 7 is a bottom plan view thereof.

The portions of the article shown in broken lines form no part of the claimed design.
